UNITED STATES PATENT OFFICE

WILLIAM J. LINNEMANS, OF BIG RAPIDS, MICHIGAN

DESIGN FOR A STAND LAMP OR ANALOGOUS ARTICLE

Application filed June 9, 1930. Serial No. 35,994. Term of patent 7 years.

To all whom it may concern:

Be it known that I, WILLIAM J. LINNEMANS, a citizen of the United States, residing at the city of Big Rapids, in the county of Mecosta and State of Michigan have invented a new, original, and ornamental Design for a Stand Lamp or Analogous Article, of which the following is a specification, reference being had to the accompanying drawing, forming a part thereof.

The figure is an elevation of a stand looking from either side thereof, showing my new design.

I claim:

The ornamental design for a stand lamp or analogous article, as shown.

WILLIAM J. LINNEMANS.
